(57) **CLAIM**

The ornamental design for a flag retirement receptacle, as shown and described.

DESCRIPTION

This application is related to co-pending non-provisional patent application Ser. No. 14/161,073, entitled "Flag Retirement Receptacle" filed on Jan. 22, 2014.

FIG. 1 is a front perspective view of a flag retirement receptacle of our new design;

FIG. 2 is a rear perspective view thereof;

FIG. 3 is a front elevational view thereof;

FIG. 4 is a rear elevational view thereof;

FIG. 5 is a side elevational view thereof;

FIG. 6 is a top plan view thereof;

FIG. 7 is a bottom plan view thereof;

FIG. 8 is a front perspective view thereof with a partially open lid;

FIG. 9 is a side elevational view with a partially open lid;

FIG. 10 is another front perspective view thereof; and,

FIG. 11 is another front elevational view thereof.

The broken lines shown in some of the figures are included for the purpose of illustrating environment and form no part of the claimed design.
